Primary Examiner — T Chase Nelson(74) *Attorney, Agent, or Firm* — Schwabe, Williamson & Wyatt, P.C.(57) **CLAIM**

I claim the ornamental design for a shoe, as shown and described.

DESCRIPTION

FIG. 1 is a front bottom perspective view of a shoe, showing my new design;

FIG. 2 is a bottom view thereof; and,

FIG. 3 is a rear bottom perspective view thereof.

The dot-dash broken line represents an unclaimed boundary of the claimed design. The broken line oval and circular structures within the boundary of the claimed design form no part of the claimed design. The broken lines depicting the remainder of the shoe show features that form no part of the claimed design.
